his Attorney

UNITED STATES PATENT OFFICE.

HARDMAN ALLGOOD GOOD, OF WHANGAREI, NEW ZEALAND.

LATCH.

Application filed October 24, 1924. Serial No. 745,547.

This invention relates to latches of the spring bolt kind and in particular to the bolt and its operation.

In the existing kinds of latch the latch body has mounted on it a knob which on being turned draws in bolt rods to the end of which is attached a spring bolt. One of the faces of the bolt end is made at present bevelled so that when the door is being closed this bevelled face may contact with another bevelled face on the door jamb fitting which causes the bolt to slide back prior to entering the socket in the jamb. This is a defect inasmuch as an appropriate tool such as a gimlet can be inserted to press against the bevel face and force it to withdraw from the socket thus unlocking the latch. Now by my invention I overcome this defect and make it impossible for the bolts to be withdrawn by the use of a tool. This is effected according to my invention by the apparatus hereinafter described.

In the accompanying drawings illustrating my invention Figure 1 is a plan view of the latch body and jamb fitting in the locked position, Figure 2 is a sectional elevation of the parts shown in Figure 1, Figure 3 shows the movable catch and attachments according to my invention, Figure 4 is an end elevation of the latch body showing the catch slot according to my invention with the bolt in withdrawn position, Figure 5 is a sectional elevation of the latch body showing the bolt in the withdrawn position.

Referring to these drawings instead of the usual bevel ended bolt I provide a bolt 1 with a substantially square or flat end 1^a. This square ended bolt can not when protruding from the latchet body be moved back by contact with the door jamb so as to enter the socket in the same way as the bevel ended bolt operates. Consequently special means are required to enable the square ended bolt to be withdrawn from and enter the socket and these means according to my invention comprise a mov-

able catch or lever 2 adapted to act in co-operation with the squared end 1^a of bolt 1. One end of the catch 2 is pivoted on a pivot 50 pin 3 within a bracket 4 which is secured by pin 5 to the latch body as shown. This catch 2 is normally pressed down by a spring 6 so that a notch or corner 7 about midway of the catch 2 engages a pin 8 fitted to the rear end of bolt 1 and so holds the bolt 1 in the withdrawn position compressing springs 9 on bolt rods 10. The movable catch 2 protrudes through a slot 11 in the front end of the latch body alongside the bolt end its end 12 being enlarged so as to come in contact during the working of the latch with a pin 13 made adjustable to ensure such contact and fitted to the door jamb fitting 14.

In operation to open the door the knob 15 is turned withdrawing the bolt rods 10 and bolt 1. The spring 6 presses the catch 2 so that the notch 7 engages the bolt pin 8 and holds the bolt 1 in the withdrawn position see Figure 5. On closing the door the enlarged end 12 of catch 2 comes automatically in contact with the adjustable pin 13 of the jamb fitting 14 which pin raises the catch 2 clear of the bolt pin 8 releasing the bolt 1 which is then forced out into the socket in the jamb by the compressed springs 9.

I claim:

In a latch, the combination with a latch body, of a spring pressed square ended bolt reciprocable in said body, a pin projecting from a lateral face of the bolt, an elongated catch pivoted to said body in a plane parallel to and at one side of the plane of reciprocation of the bolt, said catch having a notch intermediate its ends to engage said pin, an enlargement at the end of said catch opposite the pivoted end, and an adjustable pin with which said enlargement cooperates in the working of the latch.

In testimony whereof he affixes his signature.

HARDMAN ALLGOOD GOOD.
